UNITED STATES PATENT OFFICE.

WILLIAM J. CALLAHAN, OF WORCESTER, MASSACHUSETTS.

DESIGN FOR A COMBINED LAMP SUPPORT AND CASING.

58,543.

Specification for Design.

Patented Aug. 2, 1921.

Application filed December 6, 1920. Serial No. 428,830. Term of patent 14 years.

To all whom it may concern:

Be it known that I, WILLIAM J. CALLAHAN, a citizen of the United States, residing at Worcester, in the county of Worcester and State of Massachusetts, have invented a new, original, and ornamental Design for a Combined Lamp Support and Casing, of which the following is a specification, reference being had to the accompanying drawing, in which—

Figure 1 is a front elevation of a lamp support and casing, showing my new design, and

Fig. 2 is a side elevation thereof.

The device is shown attached to a temperature indicator on an automobile radiator, for which purpose it is particularly designed.

I claim:

The ornamental design for a combined lamp support and casing, as shown.

In testimony whereof I have hereunto affixed my signature.

WILLIAM J. CALLAHAN.
